United States Patent

Des. 238,774
Patented Feb. 10, 1976

238,774

COMBINED BUMPER, REAR PANEL AND TAILLIGHT ASSEMBLY

Henry G. Haga, Bloomfield Hills, and Jerry P. Palmer,
Royal Oak, Mich., assignors to General Motors Corporation

Filed Feb. 22, 1974, Ser. No. 444,864

Term of patent 7 years

Int. Cl. D12—16

U.S. Cl. D12—170

We claim:
The ornamental design for combined bumper, rear panel and taillight assembly, substantially as shown and described.
